Int. Cl. D25—04

U.S. Cl. D13—1

Des. 220,319

PAGE 2

FIG. 5

FIG. 1 is a perspective view of a building taken generally from the front and left side thereof;

FIG. 2 is a perspective view of the building taken generally from the rear right side thereof;

FIG. 3 is a front elevational view thereof;

FIG. 4 is a left elevational view thereof, and the right side being a mirror image of the left side;

FIG. 5 is a rear elevational view thereof; and

FIG. 6 is a plan view thereof but on a reduced scale.
I claim:

The ornamental design for a building, substantially as shown and described.
